UNITED STATES PATENT OFFICE.

ELBERT E. HAWKINS, OF UNADILLA, NEW YORK.

TENSION-LUG FOR SILOS AND TANKS.

1,315,120.

Specification of Letters Patent. Patented Sept. 2, 1919.

Application filed April 6, 1917, Serial No. 160,262.

Renewed December 17, 1918. Serial No. 267,188.

To all whom it may concern:

Be it known that I, ELBERT E. HAWKINS, a citizen of the United States, and resident of Unadilla, county of Otsego, and 5 State of New York, have invented an Improvement in Tension-Lugs for Silos and Tanks, of which the following is a specification.

My invention has for an object the provision of an efficient spring hook lug suitable for use in silos and tank work where swelling and shrinkage of the staves necessitate automatic compensation in the adjustment of the hoops to keep the structure 15 rigid and tight at all times.

My invention consists of a hoop lug providing two oppositely extending movable looped arms for respectively receiving the ends of the hoop and adjusting nuts, said 20 arms connected together in predetermined relation and spring pressed apart against the restraining influence of the nuts whereby they automatically maintain the hoop under tension.

25 My invention further consists of a spring hoop lug formed of a rod of steel coiled in such manner that there are provided two yielding arms having eye portions for respectively receiving the ends of the hoop, 30 said arms having normal spring action away from each other, but drawn toward each other by adjustable nuts upon the ends of the hoop, the spring action maintaining the hoop under constant tension and compensating for any variation in the circumference of the silo or tank due to swelling or shrinkage.

35 My invention also consists of the details of construction which, together with the features above specified, will be better understood by reference to the drawings, in which:—

Figure 1 is a front view of a spring hoop lug embodying my invention; Fig. 2 is a 40 side view of the same with the stave and hoop in section; Fig. 3 is a cross section of my improved spring hoop lug on line $z-z$ of Fig. 1; and Fig. 4 is a perspective view of the hoop lug.

50 2 is one of the staves of the silo or tank, which latter is circular in cross section; and 4, 4, are the ends of one of the hoops 3 which surround the silo or tank, said ends being screw-threaded and provided with adjustable nuts 5. The lug for connecting the ends of the hoop consists of a spring device formed of a coiled steel rod, the coils of

which provide two helices 7 connected by the body part 6 integral with the bottom coils, and also two spring arms 8 respectively extending in opposite directions and as continuations of the uppermost coils of the helices 7 and provided with looped ends 9 through which the respective ends 4 of the hoop extend. It will be noted that 60 these arms 8 extend over both ends of the hoop whereby it may be enabled to lie relatively close to the stave; and it will furthermore be desirable that the coils of the helices 7 shall respectively extend under and 65 over the ends of the hoop to prevent rotation of the lug when under tension. In general construction, the tension lug provides two oppositely directed spring actuated arms 8, 70 respectively looped at 9 to receive the hoop ends 4 and provide a bearing for the nuts 5 screwed upon said ends. By screwing down the nuts 5 the desired tension upon the hoop 3 may be secured; and thereafter 75 said arms will compensate for any variations 80 in tension upon the hoop due to shrinkage or swelling of the staves making up the silo or tank body. The coils 7 permit great play 85 of the arms 8 without causing them to "set" under strain, and while I prefer the proportions of these coils shown, I do not restrict myself thereto as their size and shape may be varied.

In cases where the diameters of the silos or tanks are large and further tension is 90 desirable than produced by the coils of the spring lug alone, I prefer to employ an auxiliary tension coil spring 15 which is interposed between the arms 8, 8, and maintained in position by the inwardly projecting ends 10 of the looped portions of the said arms. This spring 15 is of coiled steel and may be of any strength to suit requirements, and by substituting springs 15 of different strengths, the spring lug has capacity 100 for adjustment in addition to that under control of nuts 5.

While the lugs, positioned as they are upon the hoop ends, and against the wall of the silo or tank, are held against shifting 105 in the plane of the pull, I prefer to provide additional positioning means, such as shown at 12, said means consisting of castings each having a curved abutment flange 13 and fitting within the coil parts 7, and further secured in position by a lag screw 14. These positioning castings 12 will not only give greater security against shifting of the lug, 110 but also act as a means sustaining the lugs

when assembling them with the hoops. It is further manifest, that one of these positioning castings alone may be used with each lug and preferably the upper one.

5 The tension lugs may be made of tempered steel, or cold rolled steel without tempering where economy is a material factor. If desired, the lug may be of cold rolled steel and the reinforcing spring 15 of tempered steel. These variations are not germane to the principles of the invention, and hence may be adopted to suit special conditions as may be deemed most desirable.

10 It will now be apparent that I have devised a novel and useful construction which embodies the features of advantage enumerated as desirable, and while I have in the present instance shown and described the preferred embodiment thereof which has 15 been found in practice to give satisfactory and reliable results, it is to be understood that I do not restrict myself to the details, as the same are susceptible of modification in various particulars without departing 20 from the spirit or scope of the invention.

25 Having now described my invention, what I claim as new and desire to secure by Letters Patent, is:—

1. In a device of the character stated, the 30 combination of overlapping hoop ends and nuts, with a tension lug comprising a spring metal rod coiled into spring portions arranged respectively above and below the hoop ends and having its ends terminating 35 in oppositely directed tension arms formed with loops through which the respective hoop ends extend and upon which the nuts press.

2. In a device of the character stated, the 40 combination of overlapping hoop ends and nuts, with a tension lug comprising a spring metal rod coiled into spring portions arranged respectively above and below the hoop ends and having its ends terminating 45 in oppositely directed tension arms formed with loops through which the respective hoop ends extend and upon which the nuts press said looped portions being out of horizontal alinement.

50 3. In a device of the character stated, the combination of overlapping hoop ends and nuts, with a tension lug comprising a spring metal rod coiled into spring portions arranged respectively above and below the hoop ends and having its ends terminating 55 in oppositely directed tension arms formed with loops through which the respective hoop ends extend and upon which the nuts press said looped portions being out of horizontal alinement, and an interposed coil 60 spring between the arms to force them apart.

4. In a device of the character stated, the combination of overlapping hoop ends and nuts, with a tension lug comprising a spring 65 metal rod coiled into spring portions arranged respectively above and below the hoop ends and having its ends terminating in oppositely directed tension arms formed with loops through which the respective 70 hoop ends extend and upon which the nuts press said looped portions being out of horizontal alinement and providing oppositely directed projecting portions intermediate of the alinement of the loops, and a coil spring 75 supported by the projecting portions and interposed between the arms for forcing them apart.

5. In a device of the character stated, the combination of overlapping hoop ends and 80 nuts, with a tension lug comprising a spring metal rod coiled into spring portions arranged respectively above and below the hoop ends and having its ends terminating 85 in oppositely directed tension arms formed with loops through which the respective hoop ends extend and upon which the nuts press, and positioning castings between which the hoop ends extend said castings supporting the coiled spring portions of 90 the lug against displacement by bodily shifting in the plane of the hoop ends.

6. In a device of the character stated, the combination of overlapping hoop ends and nuts, with a tension lug comprising a spring 95 metal rod coiled into spring portions and having its ends terminating in oppositely directed tension arms formed with loops through which the hoop ends extend and upon which the nuts press, and an inter- 100 posed coil spring between the arms to force them apart, each of said looped portions and coil spring out of alinement whereby the hoop ends may be brought into relatively close parallelism and the axis of the 105 coil spring positioned to one side of a plane through the looped portions and hoop ends.

7. A spring lug for hoops of silos and tanks comprising a steel rod having its body coiled at two places and said coils both to 110 one side of the connecting rod portion and having the free ends from the opposite corresponding ends of the coiled portions bent in opposite directions so as to overlap without crossing and having their ends looped, 115 said looped ends out of alinement and also intermediate of and to the same side of the two coil portions.

In testimony of which invention, I hereunto set my hand.

ELBERT E. HAWKINS.
